UNITED STATES PATENT OFFICE.

CARL C. KING, OF BOSTON, MASSACHUSETTS.

BLADE-SHARPENING MACHINE.

1,365,696.

Specification of Letters Patent. Patented Jan. 18, 1921.

Application filed September 16, 1912, Serial No. 720,664. Renewed June 17, 1920. Serial No. 389,777.

To all whom it may concern:

Be it known that I, CARL C. KING, a citizen of the United States, residing at the Technology Chambers, 8 Irvington street, in the city of Boston, State of Massachusetts, have invented a new and useful Improvement in Blade-Sharpener Machines, of which the following is a specification.

The objects and purposes of my invention are to provide a machine for sharpening razor blades and like articles (especially safety razor blades of the detachable type) in quantities and at a very low cost, and a machine which will both grind and finish blades ready for use with a high degree of uniformity of depth of grinding and honing and of finishing or stropping, so that but little attention in this respect is required of the operator or attendant of the machine, and, further, to provide a machine which will sharpen a large number of blades within a day; this being accomplished by passing the blades and the carriers holding them along the rolls or other sharpening surfaces in an endless chain while the sharpening rolls are in motion; so that blades placed in the holders or carriers are passed along the sharpening rolls, when the carrier is swung to bring the blade into contact with each of the sharpening rolls until sharpened, and then the jaws of the blade carrier are automatically opened and the blades taken out or dropped out.

It will be seen that a machine of very great capacity may thus be devised, the capacity depending largely upon the length of the sharpening rolls and the speeds at which they are rotated.

While I show a machine adapted to grind, hone and strop new blades, it is apparent that by providing only for stropping, or for honing and stropping, or other suitable combination of abrading wheels, a machine may be used for resharpening used blades.

Other variations of the amount and character of the grinding and finishing rolls may be made to adapt the machine to work of other kinds without departing from the scope of my invention.

Referring now to the drawings:

Figure 1 is an end view of the machine with one of the sprocket wheels around which the chain runs shown in section as if cut along the line 1—1 of Fig. 3.

Fig. 2 is a detail view, part in section, of the preferable form of my blade holder or

carrier as it would appear removed from the connecting links of the chain.

Fig. 3 is a front elevation of the machine, the connecting belts and motor not being shown, and the stand or supporting frame being but partly shown. In this view, a part of the guide rails or ways for the chain of blade carriers to run on is removed, so as to show the construction of the teeth and connecting links of the chain, and a part of the end frame supporting the ways and the oscillating rails is broken away to show the driving pulleys and ends of the sharpening rolls.

Fig. 4 is a fragmentary view, part in section, of a portion of the guide rails or ways, and of one of the blade carriers and the connecting links of the chain, taken along the line 4—4 of Fig. 5, and looking in the direction of the arrows. This view shows the jaw-opening and -closing levers 34, and the character of trippers 35 employed to throw the arms or levers of the blade carriers to rotate the sleeve 9 and cam 27 of the blade carrier to open or close the jaws 31, 33, for inserting or removing a blade.

Fig. 5 is a fragmentary view of a section of two blade holders of the chain of blade carriers, as the chain would appear when running on its under guide rails or ways were the upper ways removed.

Like reference characters denote similar parts throughout the accompanying drawings.

In carrying out my invention, I preferably employ sharpening rolls 1, arranged in pairs, which rolls are spaced from each other and rotate in opposite directions, and an endless chain of pivoted blade carriers. Where a machine is adapted for grinding, honing and stropping, as in the case of sharpening new blades, I preferably form the rolls 1 in sections of, first, a coarse grinding face, second, a smooth or fine grinding face, third, a honing face, and, fourth, a finishing or stropping face. Where machines are to be used for resharpening blades, a honing and a stropping section, or a stropping section only might be provided, if desired.

To move the blade carriers along the sharpening rolls so as to present a blade held by a carrier to the rolls along a line substantially parallel with the axes of the rolls and to swing the carriers so as to bring a blade into contact with the faces of the several

rolls, I form an endless chain 2, of the blade carriers 3 (shown in detail in Fig. 2), and employ a pair of sprocket wheels 4, driven by a worm gear 17, around which sprockets 5 the chain travels. This chain consists of a tooth link 6, for engaging the ways to guide the carriers along a straight line, and for engaging the teeth of the sprocket wheels to drive the chain, and a pivot link 10, about 10 which pivot the blade carrier is adapted to swing in a plane substantially at right angles to the line of travel of the chain.

Extending between the sprocket wheels 4, I provide guide rails or ways 5, in which the 15 teeth 6, of the chain 2, slide. The ways are preferably formed of four rectangular-in-cross-section rails. To swing the carriers so as to oscillate them between the sharpening rolls, I preferably provide outer guide rails 20 7, curved, or wave-like, along that portion of the rails which lies between the end frames 13, so that the rollers 12 on the distal end of the spring 8 of each of the blade carriers follows the curved or waved guide rails, 25 thereby imparting a rocking or oscillating movement to the blade carrier, 3, causing a blade held by the jaws of the carrier to press against one roll and then the other in alternation.

30 The spring 8 is adapted to cause the carrier to press the blade yieldingly—*i. e.*, to give a springy contact of the blade against the sharpening rolls.

It is apparent that, instead of the waved 35 or curved rails, for oscillating the blade carriers, a rocker bar, with a cam to swing it, might be used without departing from the scope of my invention.

I preferably provide the chain of blade 40 carriers with rollers 14, so as to lessen the friction and to provide for a better movement of the chain along the guide rails or ways 5 and 7, and around the sprocket wheels 4.

45 The machine is, of course, provided with a suitable stand or lower frame, 18, and may be built with upper or end frames 13, supporting bearings for the sharpening rolls 1, counter shafts 22, sprocket wheels 4 and the 50 ways 5 and 7, and I preferably employ a stand or lower frame having a place for a motor 19, and having bearings for the main shaft 20, from which shaft belts 21 lead to pulleys 36 on counter shafts 22, journaled in the upper frames 13. From the center counter shaft, a chain or belt is run to a second shaft 23, carrying the worm of the worm gear 17, which drives the sprocket wheel 4. Other suitable means may be used 55 to drive the sprocket, such as miter gears and a cross shaft, or a plurality of spur gears.

From the upper and lower counter shafts, 60 22, belts are run to pulleys 36, on the shafts 37, for rotating the sharpening rolls, as in-

dicated in Fig. 1. To provide for varying the angle of grinding or sharpening blades; that is, the angle at which the blades strike the periphery of the sharpening rolls, I employ means, 24, for adjusting the rolls, the 70 said means consisting of members in which the shafts are journaled, and a screw for moving the members back and forth.

In Fig. 2 I show the detail construction of what may be called my preferred form of automatically opening and closing blade carrier or blade roller. In this form of carrier I employ a pivoting portion 25, having a smooth bore 26, through which the pivot bearing link (see 10, cross section of Fig. 1) 80 of the chain fits to form an axis for pivoting the holders. Extending to one side of, and secured to the pivoting portion, is a rod 28, around which is the inner tube or sleeve 29. This sleeve 29 is rigidly secured to the 85 end 30 of the lower jaw 31 and pinned at 32 to the rod 28 in such manner as to admit of a slight swivel or rotary movement of the sleeve 29 and of the lower and upper jaws 31 and 33, thereby providing a self-centering means for giving a full and even contact and pressure of a blade held by the jaws of the carrier when the blade is pressed against the sharpening rolls. I preferably 90 provide for this swivel action of the jaws by making the hole in the rod 28 slightly larger than the pin passing through it, though it is apparent that other suitable means might be employed. It will be noted that the upper jaw is hinged at 11 to the 95 lower jaw. To provide for automatically opening and closing the jaws 31, 33, of the blade carriers, I employ an ear or boss 15 on the upper jaw and a spring 16 at the 100 hinge joint 11 of the jaws, which spring is adapted to keep the upper jaw 33 normally open, and to cause the ear 15 on the upper jaw to press against the outer sleeve 9 of the holder. This outer sleeve 9 is cut 105 at its larger end, or the end nearest the jaws, so as to form a cam 27, which cam operates against the ear 15 on the upper jaw when the sleeve 9 is rotated to close the upper jaw 33 on the lower jaw 31 and grip a blade placed between the jaws.

To provide for rotating the outer sleeve to open or close the jaws, I employ arms or levers 34, which strike trippers 35 at points along the guide rails or ways upon which the chain travels at which it is desired to cause the jaws to open or close, so that the arms or levers 34 are thrown, and the sleeve 9 caused to rotate, and the jaws opened or closed as may be desired by the blade carrier engaging while passing one of these trippers 35 in its course of travel along the ways.

To oscillate the blade carriers, and to secure an easy yielding pressure of the blade on the sharpening rolls, the carrier is provided 130

with a flat spring 8, upon the end of which is a roller 12, which roller travels on the outer waved guide rails 7. The movement of this roller up and down so as to rock the holder on its pivot 10 is accomplished by the carrier being moved along between the rails 7 and the roller 12 following the curves or waves in the rails 7.

It will be seen that I provide a blade 10 sharpening machine of very great capacity, and a machine which will give highly uniform results, due to its being a machine of continuous operation with uniform periods of grinding, honing and finishing.

15 In operation, the sharpening rolls, driven by the motor, are rotated in the proper directions, the worm gear, also driven by the motor, rotates the sprocket wheels and drives the chain of blade carriers along the 20 ways. A blade is placed in the jaws of a blade carrier. The closing lever of the blade carrier comes into engagement with the tripper located on the ways at the feeding end of the machine, and the jaws of the carrier 25 are closed on the blade, the blade carrier then moves along the sharpening rolls where it is swung by the waved rails on its pivotal axis 10 and the blade pressed against first one and then the other of the sharpening 30 rolls. The carrier, continuing, moves around the opposite sprocket and is again brought along the ways opposite the sharpening rolls and again oscillated or swung into and out of contact with the sharpening rolls. It 35 then moves to where another tripper is located, when the opening lever engages the tripper and the jaws of the carrier are opened and the blade discharged. The carrier, continuing, moves around the sprocket, 40 and the operation is repeated.

It will be seen that by making the sharpening rolls of suitable length, and by driving the chain and the rolls at a suitable speed, the length of contact of the blades 45 on the sharpening rolls may be regulated to give extremely uniform results, inasmuch as every blade is treated like every other, thereby lessening the amount of inspection of blades necessary to insure their being properly sharpened.

It is also apparent that by providing a machine with a large number of blade carriers and making the rolls of suitable length, a very great capacity may be obtained.

55 What I claim as new and desire to secure by Letters Patent is:

1. In a blade sharpening machine, abrading rolls arranged with their axes substantially parallel, means for rotating said rolls, 60 ways substantially parallel to the axes of the rolls, an endless chain of pivoted blade carriers, mechanism for driving the chain to move the carriers along the ways, and means for swinging the carriers into and out 65 of contact with the rolls.

2. In a machine for sharpening razor blades, spaced parallel abrading rolls, means for rotating said rolls, a blade carrier movable along straight runs parallel to the axes of the abrading rolls, jaws on 70 said carrier adapted to hold blades and carry them in contact with the periphery of the abrading rolls along a line substantially parallel to the axes of the rolls, mechanism for automatically opening and 75 closing the jaws of the blade carrier, and mechanism moving the carrier so as to press a blade carried thereby against first one and then another of the abrading rolls.

3. In a razor blade sharpening machine, 80 sharpening rolls arranged in pairs, a pair of sprockets, ways connecting the sprockets, and an endless chain provided with blade carriers and arranged to move along the ways and around the sprockets, the said 85 chain being provided with teeth engaging the ways for guiding the carriers therealong, combined with means for driving the rolls and the sprockets and chain of carriers, and means moving the carriers to carry a blade 90 held thereby into and out of contact with a sharpening roll.

4. In a razor blade sharpening machine, abrading rolls arranged in pairs and rotated in opposite directions, endless ways, an endless chain, blade carriers on the chain pivoted to swing in a plane crosswise of the direction of movement of the chain, and means oscillating the carriers while they are being moved along the ways. 100

5. In a blade sharpening machine, sharpening rolls, ways, blade carriers having means engaging the ways, the carriers being arranged at right angles to the longitudinal direction of the ways, and means for moving 105 said carriers along the ways and for moving them in planes at right-angles to the longitudinal direction of the ways.

6. In a blade sharpening machine, oppositely disposed sharpening rolls and means for rotating same, channeled ways extending along a plane midway between the rolls, an endless chain having teeth and pivoted blade carriers, the teeth co-acting with the channels for guiding the carriers along the ways, 110 and means for swinging the carriers on their pivots. 115

7. In a razor blade sharpening machine, oppositely disposed abrading rolls and means imparting motion thereto, a series of 120 blade carriers pivoted between their ends, blade gripping jaws at one end of the carriers, ways about their pivotal points, a sprocket and means engaging the sprocket and the ways to move and guide the carriers 125 therealong, and guides substantially parallel with the ways and crossing the distal ends of the carriers for guiding the distal ends and for imparting an oscillatory motion to the carriers while they are being moved along 130

- the ways, whereby a blade placed in the blade gripping jaws of the carrier is brought into contact with first one and then the other of the abrading rolls.
5. 8. In a machine of the character described, an endless chain of blade carriers, sharpening rolls of different degrees of abrading power along said endless chain of carriers, and means for bringing the edge of a blade 10 held by a carrier into and out of contact with a sharpening roll, and means for moving the carrier to pass a blade held thereby along a line substantially parallel to the axis of a sharpening roll.
15. 9. In a blade sharpening machine, opposed sharpening rolls, means imparting motion to said rolls, a plurality of self-centering blade carriers joined one to the other to form an endless chain and each carrier pivoted to swing in a plane at substantially a right angle to the direction of travel of the chain, means swinging the holders about their pivotal points and means driving the chain of blade carriers to pass the carriers 20 along the sharpening rolls, ways for guiding the holders along a straight line substantially parallel to the axes of the rolls, jaws on said carriers for gripping a blade, means for opening and closing the jaws, and tripers located along the ways for engaging the opening and closing means of the jaws to automatically open and close same.
10. In a blade sharpening machine, oppositely disposed sharpening rolls and means 35 for rotating same, an endless chain of blade carriers, said carriers being pivoted to swing in a plane at right angles to the direction of movement of said chain, ways along which the chain of carriers travels, a sprocket for 40 driving the chain along the ways, wave-like guides and an extension from the pivotal point of the carriers having means engaging the waved guides for imparting an oscillatory motion to the carriers when the chain 45 is moved along the ways, to present a blade when held by a blade carrier against one and then the other of the sharpening rolls in alternation.
11. In a sharpening machine, sharpening 50 rolls and means for rotating same, an endless chain of blade carriers having blade holding jaws, said carriers being pivoted between their ends to swing in a plane at right angles to the direction of movement of said 55 chain, ways along which the chain of holders travels, sprockets for driving the chain along the ways, and waved rails crossing the ends of the holders opposite the jaws and causing the holders to oscillate on their 60 pivots when they are moved along the ways, for presenting a blade to the sharpening rolls, and a spring member between the pivot of the holder and the waved rails for easing the pressure of a blade held by a holder 65 against a sharpening roll.
12. In a sharpening machine, the combination with sharpening rolls and means imparting motion thereto, of an endless chain of pivoted blade carriers, each carrier having a pair of blade gripping jaws, a stem, 70 a movable sleeve on said stem, the said sleeve being formed to engage one of said jaws when the sleeve is moved to close the jaw, ways along which the chain of carriers travels, and trippers located along the ways 75 co-acting with means carried by the movable sleeve of the carrier to move the sleeve on the stem to close the jaws of the carrier, and means for swinging the carriers to present blades held by them to the sharpening rolls. 80
13. In a blade sharpening machine, the combination with sharpening rolls and means imparting motion thereto, of an endless chain of pivoted blade carriers, each carrier having a pair of jaws, a spring for 85 keeping a jaw normally open, a stem, a rotary sleeve on said stem, a cam on said sleeve, a co-acting projection on one of said jaws, ways for guiding the chain of carriers, and trippers located along the ways 90 engaging means carried by the rotary sleeve of the carrier for opening or closing the jaws of the carriers, and means swinging the carriers on their pivots while they are advanced along the ways. 95
14. In a machine of the character described, the combination with sharpening rolls and means for driving same, of an endless chain of pivoted blade carriers and ways for guiding the carriers along the 100 sharpening rolls, each of said blade carriers having a jaw member with a stem, a swinging jaw member having a projecting ear, a rotary sleeve on said stem, a cam on one end of said sleeve engaging the ear of the 105 swinging jaw member and closing the jaw when the sleeve is rotated, and means along the ways for rotating the sleeve, and for swinging the carriers.
15. In a blade sharpening machine, the 110 combination with sharpening rolls and means rotating same, of an endless chain of pivoted blade carriers and ways upon which the carriers travel, each of said carriers comprising a pair of jaws, a stem, a 115 rotary sleeve on said stem, a cam on said sleeve, a co-acting ear on one of said jaws, and lever arms carried by the sleeve for rotating the sleeve to open and close the jaws, and trippers located on the ways for 120 engaging the lever arms of the sleeve to rotate same, together with means for swinging the carriers.
16. In a blade sharpening machine, the combination with sharpening rolls and 125 means imparting motion thereto, of an endless chain of pivoted blade carriers, ways along which the chain of carriers moves, sprockets for driving the chain of carriers, blade gripping jaws on the carriers, a pro- 130

jection on one of the jaws, a cam for engaging the projection, and means located on the ways for operating the cam to close the jaws.

5 17. In a blade sharpening machine, the combination with sharpening rolls and means imparting motion thereto, of an endless chain of pivoted blade carriers, ways along which the chain of carriers moves, and
10 means carried by the chain for engaging the ways to guide the carriers, a sprocket for driving the chain of carriers along the ways, blade gripping jaws on the carriers, a projection on one of the jaws, a cam for engaging
15 the projection, and means located on the ways for operating the cam to close the jaws, a spring to hold the jaw normally open, and a flat spring extending from the pivotal point of each carrier and provided with a
20 roller on its distal end, and means engaging the roller and imparting a swinging motion to the carrier while it is being advanced along the ways.

18. In a blade sharpening machine, rotatable sharpening rolls, an endless chain of blade carriers, ways for guiding the carriers, said carriers comprising blade-gripping jaws, a stem, a sleeve on said stem, a cam on the sleeve, a co-acting projection on one
25 of the jaws, and lever arms carried by the sleeve, together with tripping dogs located on said ways for engaging said lever arms and rotating the sleeve and cam to close the jaws of the blade carriers, and a spring for
30 keeping the jaws normally open.

19. In a blade sharpening machine, the combination with sharpening rolls and means for rotating same, of an endless chain of blade carriers comprising a tooth link
35 and a pivot link pivotally joined to one another to form a chain, blade gripping jaws having stems pivotally mounted on the

pivot link of said chain and having a flat spring extending laterally thereof, ways upon which the chain travels, and means 45 parallel with the ways for operating against the spring to swing the jaws on their pivots, together with mechanism for driving the chain.

20. In a blade sharpening machine, oppositely disposed sharpening rolls and means for rotating same, pivoted blade carriers, ways extending along a line symmetrical to the axes of each pair of abrading rolls, the said ways having channels or slots, teeth co-acting with the channels of the ways to guide the carriers along the ways, a pivoting member connected to each of the teeth to form an endless chain and carrying the blade carriers, a sprocket for engaging the 60 teeth of the chain to move the chain of carriers along the ways, and means for swinging the carriers on their pivots while they are being advanced along the ways.

21. In a blade sharpening machine, sharpening rolls and means for rotating same, an endless chain, blade carriers pivoted about the axis of said chain to swing in a plane at right angles to the longitudinal direction of the chain, ways for guiding the chain, 70 blade gripping jaws on said carriers, guides parallel with the ways and engaging the carriers to swing them on their pivots, and a spring for easing the pressure of a blade held by a blade carrier when swung into 75 contact with a sharpening roll.

In testimony whereof I have signed my name to this specification in the presence of two subscribing witnesses.

CARL C. KING.
